ATTORNEY

UNITED STATES PATENT OFFICE.

ANNIE CLELAND, OF NEW ORLEANS, LOUISIANA.

FLOWER-BOX.

SPECIFICATION forming part of Letters Patent No. 409,925, dated August 27, 1889.

Application filed May 15, 1889. Serial No. 310,918. (No model.)

To all whom it may concern:

Be it known that I, ANNIE CLELAND, of New Orleans, Orleans parish, Louisiana, have invented a certain new and useful Improvement in Flower-Boxes, of which the following is a specification.

My invention consists in a new and improved flower-box, which will be hereinafter fully described and claimed.

10 Referring to the accompanying drawings, Figure 1 is a perspective view of my improvement as applied in position to a window-frame. Fig. 2 is a top plan; and Fig. 3 is a cross-section on line 3 3, Fig. 2.

15 The same numerals of reference indicate corresponding parts in all the figures.

The common flower-boxes and clay flower-pots when placed on window-sills to hold flowers and plants have many disadvantages.

20 They are very dangerous, and they are liable to fall out from window-sills or from shelves and kill or cripple persons passing under them at the time. They also rot and destroy window-sills and ruin the paint on the side of

25 houses from the dirty water that drips from them when the plants are watered, and injure the clothes of persons passing beneath them. They are not ornamental, and are very dangerous in stormy weather from their liability

30 to be blown off the sill.

The object of my invention is to overcome these difficulties, and I attain this object by the construction which will be now described.

A indicates a strong metal box, that may be 35 of any preferred shape, but is preferably made in a curved or somewhat crescent form, as shown, so as to fit neatly against the outside of a window-sill, as shown in the drawings, its flat rear side fitting against the sill, while the

40 central part of the said side is bent in to leave a space between it and the outside of the sill, as shown. This box is made preferably of tin and zinc, and is held and supported at the window by two strong iron bars B B. The

45 lower half of these bars B is bent to fit the bottom and rear side of the box A, their lower ends being bent up at right angles and fitting up into pockets a a in the bottom of the box, as shown in the sectional view, Fig. 2, of the

50 drawings, while at the back of the box the bars pass through metal clips a' a', which hold

the box firmly to the bars. At b b the bars are bent to pass over the window-sill, and are then bent up at right angles, as shown, having apertures b' at their upper flattened and enlarged ends b². The box A fits against the window-sill, and the iron bars fit up over the sill and up to each side of the window frame or casing, and are secured at the window by strong screws C C, passing through the apertures in the upper ends of the bars, and by strong iron staples D, usually three to each bar, as shown. Within the box A is placed a perforated false bottom E, which is supported above the solid bottom of the box on raised 65 interior end supports a² a² and a central cross-bar a³.

The earth in which the flowers are to be planted is placed in the box, resting on the perforated false bottom, and when the flowers 70 and plants growing in this earth are watered the water drips from the earth through the perforated false bottom down upon the solid box-bottom, and is drawn off through a spout a⁴, which is kept closed by a cork a⁵, into a 75 cup F, which is removably suspended in position by its wire bail-handle f, being hung on a hook g, secured to the back of the box. Dirt and settling in the bottom of the box are cleaned out through the spout a⁴. 80

The boxes are made of different sizes, according to the size of the window.

From the foregoing description, taken in connection with the accompanying drawings, my invention and its advantages will be readily understood.

It will be seen that my new and improved flower-box is simple and strong in construction and very efficient and satisfactory in use. It will be of special value to the many persons 90 in large cities who have no garden in which to plant flowers, as it can be set on a balcony or porch, or in almost any position.

The box is finished in an ornamental manner, as shown in the drawings.

Having thus described my invention, what I claim, and desire to secure by Letters Patent, is—

1. The flower-box A, curved in at its rear side to form the rectangular recess and having the rear discharge-opening in said recess, the perforated false bottom supported above

its solid bottom, and the supporting-bars BB, substantially as set forth.

2. The combination of the box having the pockets *a*, the rear clips, and the discharge-opening, a perforated false bottom, and the bent supporting-bars having the upwardly-bent lower ends, substantially as set forth.

3. The combination of the box having the pockets *a*, the rear clips, and the discharge-opening, the perforated false bottom, the bent supporting-bars having the upwardly-bent lower ends and perforated upper ends, the

screws, and the staples, substantially as set forth.

4. The combination of the box having the 15 pockets *a*, the internal end supports and cross-bar, the discharge-opening, and the rear clips, the cork, the perforated false bottom, and the supporting-bars, substantially as set forth.

ANNIE CLELAND.
